UNITED STATES PATENT OFFICE.

HENRY J. HUBERT, OF ST. LOUIS, MISSOURI, ASSIGNOR TO JOHN T. MILLIKEN, OF ST. LOUIS, MISSOURI.

CAPSULE-MACHINE.

1,269,448.

Specification of Letters Patent. Patented June 11, 1918.

Application filed October 1, 1917. Serial No. 194,297.

To all whom it may concern:

Be it known that I, HENRY J. HUBERT, a citizen of the United States, and a resident of the city of St. Louis and State of Missouri, have invented a new and useful Improvement in Capsule-Machines, of which the following is a specification.

This invention relates to capsule machines. It has more particularly to do with that portion of the machine known as the first container or receiver for the formed capsule shell, which coöperates with the cutting-off mechanism for trimming the end of the shell to size.

In machines of this character, the formed capsule shells are made to travel through conducting tubes and into the receivers by gravity and suction. Owing to the prevailing construction and arrangement of the movable coöperating parts of the mechanism of such machines, it has been heretofore difficult to maintain, at all times, sufficiently tight joints between the meeting parts to prevent leakage of air, resulting in the choking of the tubes and the incomplete reception of the shells into the receivers.

The present invention, therefore, has for its principal objects to maintain air-tight joints; to secure simplicity of structure and facilitate its installation in machines of the character above set forth without altering the present parts which coöperate therewith; to insure constancy and precision of operation; and to attain certain advantages as will hereinafter more fully appear.

In the accompanying drawings illustrating a practical adaptation of the invention,—

Figure 1 is a fragmentary view, partly in side elevation and partly in section, showing only so much of the machine as directly concerns the invention;

Fig. 2 is a view, on an enlarged scale, partly in end elevation and partly in section, showing the valve arrangement between the receiver-tube and the suction-pipe;

Fig. 3 is a similar view showing the receiver-tube moved to position to cut off communication with the suction-pipe;

Fig. 4 is a section through the receiver-tube and the coöperating trimming mechanism, the receiver-tube being in receiving position and a capsule shell being shown in the receiver;

Fig. 5 is a similar view showing the receiver-tube moved to position to discharge the capsule shell, the shell being shown as moved onto the mandrel of the trimming mechanism by the ejector;

Fig. 6 is a fragmentary top plan view of the trimming mechanism; and

Fig. 7 is a front elevation thereof.

Referring now to the drawings, a portion of the supporting frame of the machine is indicated by the numeral 1. Journalled in the frame is a tube 2 whose ends are closed. On one end of the tube is a crank 3 which, in practice, is connected to suitable actuating mechanism (not shown) whereby the tube 2 is given an intermittent oscillation or partial rotation as will be hereinafter more fully described.

Extending diametrically through the tube 2, hereinafter referred to as the receiver-tube, is a multiplicity of tubular receivers 4 for the capsule shells. Fitted slidably in the receivers are ejectors 5 having elongated stems 6 extending loosely through apertures in an actuator-bar 7 and being screw-threaded at their ends to receive jam nuts 8 which normally abut the outer face of said actuator-bar. On the stems 6 are collars 9, and sleeved on said stems are springs 10, which bear at their ends against said collars 85 and the inner face of the actuator-bar 7.

Coöperating with the receiver-tube 2 is a shoe 11 comprising a concavo-convex bar having angular bracket extensions 12 at its ends which are slotted to receive bolts 13, whereby said bar is secured to the frame members 1 in adjustable relation to said receiver-tube. The circumference of the receiver-tube and the concaved inner face of the bar are ground with exact nicety to produce an air-tight joint while permitting rotation of said tube.

The actuator-bar 7 is mounted slidably on parallel guide-pins 14 projecting from the receiver-tube 2, and it is yieldably held in normal position by springs 15 sleeved on said guide-pins between it and the tube. This actuator-bar is pressed toward said receiver-tube by cams or levers (not shown) in properly timed order during the operation of the machine as will be presently pointed out.

The conducting tubes 16, of which there is one for each of the receivers 4, are joined at their ends to the shoe 11 so as to register

with the respective receivers 4 when the latter are set vertically, as shown in Fig. 4, in which position the capsule shells, indicated by the numeral 17, are drawn into the receivers 4 by suction due to a partial vacuum created in the tube 2 in a manner now to be described, there being a series of apertures 18 in the receivers at or adjacent to the end of the ejector 5.

- 10 Near the end of the tube 2 opposite to that at which the crank 3 is applied, is an opening 19 which registers with an opening in the end of a pipe-coupling 20 to which a suction-pipe 21 is attached (see Figs. 1 and 2). The coöperating end of the coupling is rounded out to correspond to the curvature of the tube 2 and it is preferably provided with a bushing 22, the bearing face of which is ground to produce an air-tight joint with the tube 2.

On opposite sides of the tube 2, the coupling 20 is provided with lugs 23 from which depend studs 24 on which the apertured end portions of a yoke 25 are loosely sleeved. This yoke is provided with a pair of rollers 26 engaging the tube 2, and it is held in place by jam-nuts 27 on the ends of the studs 24, springs 28 being sleeved on said studs and under compression between said lugs 23 and washers 29 resting on the end portions of said yoke.

When the receivers 4 are in receiving position, as shown in Fig. 4, the opening 19 in the tube 2 establishes communication with the suction pipe 21, as shown in Fig. 2. After the capsule shell 17 is drawn into the receiver 4, the tube 2 is given a partial rotation, approximately a quarter turn, or more or less, as the case may be, according to the relative arrangement of the coöperating parts of the machine. This moves the opening 19 out of register with the opening in the coupling 20, and as the opening 19 is exposed, as shown in Fig. 3, atmospheric pressure is restored within the tube 2. This actuation of the tube 2 brings the receivers 4 in alinement with the mandrels 30 of the trimming mechanism, and immediately thereafter, the actuator-bar 7 is moved in the usual manner toward the tube 2, by the mechanism not shown, but which will be the same as it has heretofore been employed in machines of this character. The ejectors 5 are thereby actuated to effect the transfer of the capsule shells from the receivers 4 to the mandrels 30 (see Fig. 5). The shells are then trimmed to size in the same manner in which it has heretofore been done.

The trimming mechanism need not be altered in the least in the application of the present invention to the machine. Hence, only so much thereof as coöperates directly with the present structure is illustrated in a fragmentary and schematic manner. In Figs. 4, 6 and 7 of the drawings, a well-

known type of cutting-off mechanism is shown. In this form the mandrels 30 are arranged in pairs, each pair having a stripper common thereto. The stripper, indicated by the numeral 31, is given a double actuation. That is, it is first reciprocated to discharge the trimmed capsule shell, and a second time to discharge the waste material from the two companion mandrels.

The circular cutting knives 32 also co-operate with two mandrels. These knives are given a partial rotation in each direction when actuated, and their marginal portions travel in close relation to one side of grooves 33 in the mandrels 30 so as to shear the capsule shell, the mandrels being also rotated reversely to said knives, but at a greater speed, owing to the smaller pinions 34 on the mandrels being in mesh with the larger pinions 35 on the spindles of the knives.

The cutting knives 32 are provided, as usual, with the diametrically-opposite marginal recesses 36 which are opposite the mandrels 30 when the knives are at rest, so as to make clearance for the capsule shells in placing them on and removing them from the mandrels.

By the employment of a structure as herein set forth, the number of separate parts is minimized and the mechanism simplified, in addition to the prevention of air leakage and the avoidance of interference in the operation of the machine by lessening the possibility of foreign particles getting between the movable parts.

Obviously, the structure admits of considerable modification without departing from the spirit and intent of the invention as defined by the appended claims. Therefore, it is not limited to the construction and arrangement shown.

What is claimed is:

1. In a capsule machine, in combination with the usual conducting device for the formed capsule shell, and the trimming mechanism for the shell, a shoe through which the conducting device extends, and a suction-controlled receiver for the capsule shell, said receiver being movable alternately in air-tight engagement with said shoe into coöperative relation to said conducting device and to said trimming mechanism.
2. In a capsule machine, in combination with the conducting device for the formed capsule shell, and the trimming mechanism for the shell, said conducting device comprising a tube, and said trimming mechanism comprising a mandrel and a cutting knife coöperating therewith, a shoe through which said tube of the conducting device extends, said shoe having an arcuate face, a suction-controlled receiver-tube in rotatable engagement with the arcuate face of said shoe, a tubular receiver disposed trans-

versely in said receiver-tube and being transversely apertured, and an ejector in said receiver, said receiver-tube being moved to bring said receiver alternately into alinement with said conducting tube to receive the capsule shell therefrom and with the mandrel of the trimming mechanism to effect the transfer of the shell to said mandrel.

3. In a capsule machine, a rotatable receiver-tube having a tubular receiver disposed transversely therein, and an ejector movable longitudinally in said receiver, said receiver being transversely apertured adjacent to said ejector, a shoe having an articulated face in air-tight contact with which said receiver-tube moves, a conducting tube for the formed capsule shell extending through said shoe, a trimming device comprising a mandrel and a cutting knife coöperating therewith, said mandrel and said conducting tube being disposed radially in coöperative relation to said receiver-tube at an angle to each other but in the same axial plane with said receiver, whereby the receiver is brought alternately into alinement with said conducting tube and said mandrel when the receiver-tube is oscillated, and a suction-pipe having a coupling with which said receiver-tube is rotatably engaged, said receiver-tube having an opening so correlated to said receiver and the suction-pipe coupling that, when the receiver is in coöperative relation to said conducting tube, communication is established with said suction-pipe to draw the capsule shell into the receiver, and when the receiver is moved into coöperative relation to said mandrel of the trimming device, atmospheric pressure is restored in said receiver.
4. In a capsule machine, a receiver for the formed capsule shell, the same comprising an oscillatory tube, a tubular receiver disposed transversely in said tube, said receiver being transversely apertured and having an ejector movable longitudinally therein, a shoe with which said oscillatory tube has an air-tight rotatable engagement, and a conducting tube extending through said shoe radially with respect to the axis of said oscillatory tube.
5. In a capsule machine, a receiver for

the formed capsule shell, the same comprising an oscillatory tube, a tubular receiver disposed transversely in said tube, said receiver being transversely apertured and having an ejector movable longitudinally therein, a shoe with which said oscillatory tube has an air-tight rotatable engagement, a conducting tube extending through said shoe radially with respect to the axis of said oscillatory tube, whereby said receiver may be brought into alinement with said conducting tube, a suction-pipe having a coupling with which said oscillatory tube is rotatably engaged, said oscillatory tube having an opening whereby, when said receiver and said conducting tube are in coöperative relation, communication is established with said suction-pipe and the capsule shell is drawn into the receiver, and when said receiver is moved out of such relation to said conducting tube, atmospheric pressure is restored in the receiver.

6. In a capsule machine, a conducting device for the formed capsule shell, and a receiver for said shell, said receiver being suction-controlled and having an air-tight slidable engagement with said conducting device.

7. In a capsule machine, a shoe having a row of conducting tubes extending therethrough for the formed capsule shells, a receiver-tube having an air-tight rotatable engagement with said shoe, said receiver-tube having a multiplicity of tubular receivers disposed transversely therein in correlation to the respective conducting tubes, a trimming mechanism comprising a multiplicity of mandrels and cutting knives coöperating therewith, there being one of said mandrels correlated to each of said receivers, said receiver-tube being oscillated to bring said receivers alternately into coöperative alinement with said conducting tubes and with said mandrels of the trimming mechanism, a suction-pipe, and means for establishing communication between said suction-pipe and said receivers when the latter are in coöperative relation to said conducting tubes.

Signed at St. Louis, Mo., Sept. 29, 1917. 100

HENRY J. HUBERT.
